UNITED STATES PATENT OFFICE.

WILLIAM F. TROAST, OF LANCASTER, PENNSYLVANIA, ASSIGNOR TO THE SLAYMAKER-BARRY COMPANY, OF SAME PLACE.

PADLOCK.

SPECIFICATION forming part of Letters Patent No. 572,586, dated December 8, 1896.

Application filed April 16, 1895. Serial No. 545,857. (No model.)

To all whom it may concern:

Be it known that I, WILLIAM F. TROAST, a citizen of the United States, residing in Lancaster, in the county of Lancaster and State 5 of Pennsylvania, have invented certain Improvements in Padlocks, of which the following is a specification.

This invention relates to improvements in that class of devices employed for locking the 10 wheels of bicycles, or in securing other mechanisms or parts in which a chain or similar device is necessary to embrace the members to be locked together; and the object of the 15 invention is to produce a lock of the character described that is cheap and simple in construction and strong and reliable in use.

The invention consists, first, in the mechanism for locking in the case the plug or bolt by which the detachable end of the chain is 20 secured to said case, and, second, in the construction and combination of the various parts, as hereinafter fully described, and then pointed out in the claims.

In the accompanying drawings, which form 25 a part of this specification, Figure 1 is a face view of the lock-case, and Fig. 2 an edge view of the same. Fig. 3 is a perspective view of the interior of the bottom of the case, the operating parts being removed; and Fig. 4, a 30 similar view of the top of the case. Fig. 5 is a perspective view of the bottom of the case, showing the plug or bolt locked therein; and Fig. 6, a top plan view of the same, showing the bolt and the spring actuating the same 35 removed. Fig. 7 is a vertical section of the entire lock-case on broken line 7 7, Fig. 3. Fig. 8 is a side view of the key. Fig. 9 is a bottom view of the locking-levers, showing the bolt engaged thereby; Fig. 10, a similar 40 top view of the same; Fig. 11, an edge or side view of the locking-levers and bolt, occupying the position shown in Fig. 10, and having a part cut away; Fig. 12, a top view of said levers, the parts being shown in the position 45 occupied thereby as the bolt is being ejected from the case; and Fig. 13, an edge or side view of the same. Fig. 14 is a rear end view of the locking-levers, and Fig. 15 a face view of the keyhole-guard. Figs. 16, 17, and 18 50 are perspective views of a modified construction of the locking-levers, showing their application to a fast-shackle lock.

Similar letters and numerals indicate like parts throughout the several views.

In the lock shown the case thereof is divided edgewise parallel with its sides, and for the purposes of this specification the half of the case containing the principal parts for holding the operating mechanism in place is called the "bottom," and the other half the "top," similar relative terms being employed to designate the leaves of the locking-lever.

Referring to the details of the drawings, A indicates the bottom of the case; A', the top; A², the wing to which the chain is permanently attached; A³, the wing in which is secured the bolt carrying the detachable end of the chain; a, the rivet-holes through the wings, and a' the rivets engaging said holes, whereby the top and bottom of the case are fastened together.

B indicates the binding-chain, the central portions of which are cut away; B', the clevis by which one end of the chain is connected directly with the case; B², the clevis connecting the chain with the bolt, and b the pins 75 securing the clevises to the case and bolt.

In wing A³ of both the bottom and top of the case is formed a longitudinal groove, d, extending from the outer end of said wing 80 into the recessed main portions, D D', respectively, of said bottom and top, which grooves, when the parts of the case are united, form an opening through which the bolt E is inserted; and extending back from the inner 85 ends of said grooves are registering ribs d', the outer edges of which range with the bottoms of said grooves and direct the end of the bolt E, so as to engage the same between the leaves of the locking-lever. On the sides 90 of and parallel with ribs d' are ribs d² and d³, the ribs d² having shoulders on their inner ends, with curved recesses d⁴ formed therein, the rims of which recesses form wards that engage notches K' in the key; and in the 95 top of the case, back of rib d', is a stud, d⁵, also having a curved recess, d⁶. The ribs d² of the top register with the ribs d² d³ of the bottom, and the stud d⁵ of the top, with the inner end of a key-guide in the bottom, as shown in 100 Fig. 7.

In the sides of the top and bottom of the case are registering semicircular recesses e, having wings e', which together form the key-

hole E', (shown in Fig. 2,) and inside of these recesses are curved sockets e², in which is located the usual annular keyhole-guard, F. (Shown in Fig. 15.) In the bottom of the case and extending inward on opposite sides of the keyhole are parallel ribs e³, forming a key-guide, the inner ends, e⁴, of said ribs being reduced in height, to afford space for the movement of the upper locking-lever. Between ribs e³ are wards e⁵ e⁶, having concave upper edges, the ward e⁶ registering with stud d⁵.

A rib, f, extends back from the rib e⁴ on the side of the key-guide opposite the bolt-opening, and has on its end two posts, f', forming a groove, f², at right angles with said bolt-opening; and opposite posts f' are similar posts, f³, also forming a groove, f², which ranges with the groove between posts f'.

G and H indicate, respectively, the top and bottom locking-levers. Each of these levers has a broadened leaf forming its forward end and a reduced shank, g and h, respectively, forming the rear end. On the sides of each shank are trunnions, g' h', adapted to engage the grooves, f², between posts f' and f³, the trunnions g' resting in said grooves above trunnions h'. Behind the trunnions the inner faces of shanks g and h are hollowed out, as seen in Fig. 14, and in the cavities thus formed there engage the ends of a coiled spring, S. The ends of the trunnions g' h' on each side of the levers are held in their proper relative positions, or are bound together, by collars I, embracing the same inside of posts f' f³, whereby action of spring S serves to close the leaves of the levers upon each other. The leaf of lever G has a longitudinal slot, g², therein constructed to take over stud 5, to allow free play for said leaf; and a neck, h², connects one side of the leaf of lever H with a side of its shank h, said neck playing in a channel, a², between rib d² of the bottom of the case and the end of the key-guide. In the free end of each leaf is a cross-shaped opening, i, the longitudinal arm, i', of which extends through said end, dividing the same into jaws, the inner edges of the ends whereof are beveled, as shown at i²; and in the inner faces of the leaves, just back of the transverse parts of openings i, are transverse registering grooves m, forming a channel for the end, M, of a spring coiled around a post, N, located outside of rib d² of the bottom of the case.

The end m' of said spring bears against the wall of the case, and end M passes between the adjacent ribs d² of the top and bottom of said case inside of the shoulders on said ribs. In rear of grooves m the inner faces of the leaf of lever G and the neck h² of lever H are concave in outline, as seen at m², Figs. 11 and 13, to facilitate the engagement therewith of bits K² of the key.

E indicates a bolt, the head R' of which has a perforation, r, through which clevis B² is connected therewith. On the inner end of the bolt is a cross-shaped stem, r', adapted to

engage the cross-shaped openings, i, of the levers G and H. The engagement of the wings r² of stem r' with the wings i³ of said openings locks the bolt in the case. When the bolt is so locked, the leaves of the levers are closed upon each other and the stem r' engaged with the openings i of both levers, the wings, r², of the bolt-stem interlocking with the wings, i³, of openings i, and the spring M lies in the channel formed by grooves m. To unlock the bolt, the key is revolved in the lock so as to spread the leaves of the levers apart and release the spring M, when said bolt is automatically ejected by engagement of the spring therewith, as shown in Figs. 12 and 13. While the bolt is detached from the lock, spring M maintains the position illustrated in those figures, thus holding the levers open to reengage the bolt therewith, which is done by forcing it inward until said spring is pushed back into channel m m and the openings i again embrace stem r', the beveled edges, i², of the jaws of the levers facilitating the engagement of the bolt therewith.

The locking-levers G and H are located with their faces parallel with the faces or top and bottom of the case, so that the top and bottom plates of said case limit the movement of the vibrating ends of the locking-levers when opened to release the bolt, thus avoiding the necessity of the construction of any special device for that purpose. The stem of the bolt and the openings in the vibrating ends of the locking-levers are rectangular in outline, to prevent the twisting and turning of the bolt in the lock-case, to prevent rattling and wearing of the parts.

Two levers are employed to more surely prevent disengagement of the bolt by accidental jarring open of either one thereof, as the tension of spring S will cause the leaves of the levers to follow the movements of each other, so that either one or the other of the openings i would be engaged with stem r'. One lever, however—the upper, for instance—could be used alone by lessening the depth of the grooves in which its trunnions rest and by bearing the lower end of spring S on the bottom of the case; and instead of rib d² a bearing could be formed for the leaf of the lever by substituting a platform for said rib, as shown by broken lines t, Fig. 3, and making the top thereof flush with the bottom of groove d.

It will be observed that the upper lever is thicker than the lower. This is to avoid undue thickness of the lock, and because the upper lever has more play in the case than the lower and, engaging more of the bolt, has more strain put upon it. These locking-levers can be applied in different ways to securing bolts in position. In Figs. 16 and 17 they are shown as applied to securing in position a sliding bolt, 2, adapted to engage the swinging arm, 3, of a fast-shackle in the case. With this construction the bolt 2 is held permanently between the leaves 4 of the levers and has a

longitudinal movement between the same. When the bolt-head 5 is engaged with the notch 6 of the swinging arm of the shackle, as shown in Fig. 16, the ends of leaves 4 about 5 against the back of said head, to prevent the same from becoming accidentally detached from said notch, the leaves of the lever being held apart by the stud 7 on the back of head 5. In turning the key to detach the bolt from the shackle, bits thereon first engage the inner faces, 8, of leaves 4 and spread them apart, which being done another bit bears against shoulder 9 of the bolt and forces said bolt out of engagement with the notch 6 and back into the position shown in Fig. 17.

I do not confine myself to the details of construction herein shown and described, as it is obvious that many alterations may be made therein without departing from the principle 20 and scope of my invention; neither do I restrict myself to the application of the locking-levers or the bolt to any particular kind of lock.

Having thus described my invention, what 25 I claim as new, and desire to secure by Letters Patent, is—

1. The combination, in a lock, of a bolt having shoulders on opposite sides thereof, a jaw having a recess therein constructed to 30 embrace both said sides of the bolt, and shoulders in opposite sides of said recess and adapted to interlock with the shoulders on both sides of the bolt.

2. The combination, in a lock, of a bolt 35 having shoulders on opposite sides thereof, jaws, each of which has a recess therein constructed to embrace both said sides of the bolt, and shoulders in opposite sides of the recess of each of the locking-jaws and adapted 40 to interlock with the shoulders on both sides of the bolt.

3. The combination, in a lock, of a bolt 45 having shoulders on opposite sides thereof, a pair of lever-jaws, each of which has a recess therein constructed to embrace both said sides of the bolt, shoulders in opposite sides of the recess of each of the locking-jaws and adapted 50 to interlock with the shoulders on both sides of the bolt, and an expanding spring located between the rear arms of the levers, for the purpose specified.

4. The combination, in a lock, of a bolt, a pair of levers adapted to close upon each other and secure the bolt in a fixed position, trunnions formed with each of said levers and constituting the fulcrums thereof, and means 55 for securing the trunnions in position.

5. The combination, in a lock, of a bolt, a pair of levers having trunnions thereon, collars embracing the corresponding trunnions of the levers, and jaws on the levers in front of the trunnions and adapted to lock the bolt in a fixed position.

6. The combination, in a lock, of a bolt, a pair of spring-actuated levers having trunnions thereon, collars embracing the corre-

sponding trunnions of the levers, and jaws on the levers in front of the trunnions and adapted to lock the bolt in a fixed position.

7. The combination, in a lock, of a bolt, a pair of levers having trunnions thereon, collars embracing the corresponding trunnions of the levers, jaws on the levers in front of the trunnions and adapted to lock the bolt in a fixed position, and an expanding spring located between the arms of the levers in rear of said trunnions, for the purpose specified.

8. In a lock, the combination, with a bolt, of a pair of levers having trunnions on the sides thereof, collars embracing the trunnions, jaws on the levers and in front of the trunnions, said jaws being adapted to embrace said bolt and lock the same in a fixed position, and an expanding spring located between the arms of the levers in rear of said trunnions, for the purpose specified.

9. The combination, in a lock, of a case having a bolt-opening therein, a pair of vibrating jaws, a bolt constructed to engage said bolt-opening and interlock with the vibrating jaws, a spring engaged between said jaws and adapted to be released therefrom by the disengagement of the jaws from the bolt, to eject the bolt from the case.

10. In a lock, the combination, with a case 95 having a bolt-opening, of a pair of levers disposed lengthwise in front of said opening, trunnions on the sides of the levers and engaging grooves in the case, means for binding the trunnions in their relative positions, 100 jaws on the front arms of the levers and having T-shaped recesses therein, an expanding spring located between the arms of the levers and behind the trunnions, and a bolt constructed to engage the bolt-opening and having 105 a T-shaped head adapted to interlock with the T-shaped recesses in said jaws.

11. In a lock, the combination, with a case having a bolt-opening, of a pair of levers disposed lengthwise in front of said opening, 110 trunnions on the sides of the levers and engaging grooves in the case, means for binding the trunnions in their relative positions, an expanding spring located between the arms of the levers behind the trunnions, jaws on the 115 front arms of the levers and having T-shaped recesses therein, ribs extending inward from the bolt-opening and ranging with the stem of said T-shaped recesses and having their free edges forming a prolongation of the top 120 and bottom surfaces of the key-opening, and a bolt constructed to engage said bolt-opening and having a T-shaped head adapted to interlock with the T-shaped recesses in the jaws.

12. In a lock, the combination, with a case having a bolt-opening, of a pair of levers disposed lengthwise in front of said opening, trunnions on the sides of the levers and engaging grooves in the case, means for binding 125 the trunnions in their relative positions, an expanding spring located between the arms

of the levers in rear of the trunnions, jaws on the front arms of the levers and having T-shaped recesses therein, transverse grooves formed in the inner faces of the levers behind said recesses, a bolt constructed to engage said bolt-opening and having a T-shaped head adapted to interlock with the T-shaped recesses in the jaws, and a spring engaging said transverse grooves in the levers and adapted to eject the bolt when disengaged from said levers.

13. In a lock, the combination, with a case having a bolt-opening, of a key-guide perpendicular to the direction of said bolt-opening, a pair of levers disposed lengthwise in front of said opening, trunnions on the sides of the levers and engaging grooves in the case, means for binding the trunnions in their relative positions, an expanding spring located between the arms of the levers in rear of the trunnions, a jaw forming the front arm of the lower lever and connected with the rear arm thereof by a neck playing in a groove in rear of said key-guide, a jaw forming the front arm

of the upper lever and passing over the rear end of the key-guide, the free ends of said jaws having T-shaped recesses formed therein, and a bolt constructed to engage said bolt-opening and having a T-shaped head adapted to interlock with the T-shaped recesses in the jaws, substantially as and for the purpose specified.

14. The combination, in a lock, of a bolt having a T-shaped head, a pair of levers adapted to vibrate in a plane perpendicular to the faces of the case and having T-shaped recesses in their front ends, said recesses being constructed to embrace the edges of said head, trunnions on the sides of the levers, collars embracing the trunnions, and an expanding spring between the arms of the levers in rear of said trunnions, for the purpose specified.
